[57] ABSTRACT

Improvements in pads for feminine use, of the type for internal application, said pad comprising a dehydrated pressed cellulose body, of high moisture absorbent characteristics, said body being thin and flat and being straight at one end thereof, said cellulose body being included in the interior of a sheath made of solid jelly which is shaped similar to the interior body, said sheath being circular and rounded adjacent the other end of said body, said jelly dissolving by the thermic action of the human body, and said sheath acting as a lubricator for making the application of the pad easier, aided at the same time by the flat shape of same.

FEMININE USE PADS

The present invention refers to some improvements on pads for feminine use.

At present, the internal-use feminine pads which are known on the market are those of the type which comprise a cylindrical body of absorbent material and provided with a traction thread on one of its ends. These actual pads, which are known on the market, have the inconvenience of being excessively bulky, therefore requiring a large container which is uncomfortable to carry. Also, due to its size and its considerable section, its application is rather difficult.

In order to eliminate the before mentioned inconveniences, the improvements which are the object of the present invention have been contrived, which give as a result a new kind of pad, provided with peculiarities which make it much more advantageous than other devices meant for the same purpose.

These advantages are the following:

1. The pad is easily applied, due to its special shape and characteristics.
2. The pad has a minimum volume per unit, which allows the use of small containers, provided with a great number of pads.
3. The pad has high absorbent power, and is greatly imbibent.
4. The pad is covered by a solid jelly-like material for lubrication purposes and for making the pad relatively rigid, thus making application very easy, and which jelly-like material is easily dissolved by body heat.

Generally speaking, the improvements included in the object of the present invention include a dehydrated and pressed cellulose body, of high moisture imbibent characteristics, which is provided with a coating or sheath made up of a solid jelly-like material.

The above mentioned sheath can exhibit a continuous wall or layer, which has no effect whatsoever for the passage of moisture and secretions towards the internal pressed body, as the mentioned sheath, due to its characteristics mentioned above, easily dissolves with body heat.

In another variation of the invention, there is the possibility of providing the walls of the sheath and the central body with borings, which would be of aid for the passage of moisture towards the interior pressed cellulose body, thus establishing passages or inlets for the flow, which enter the cellulose interior body making it expand or swell so that it becomes almost as thick as as it is wide, the body thus acquiring its normal volume of use.

The mentioned coating applied to the cellulose body is made of solid jelly or other jelly like products.

Another of the variations comprises several borings in the pad through which the traction thread passes, thus describing a sinuous run for same, which will give it much more strength.

In another variation, the traction thread is made up starting from a thread which is sewn lengthwise on the pad, the prolongation or extension of which gives place to the end of the traction thread. Said thread exhibits very loose stitches, thus allowing the expansion or swelling of the pad.

In all the mentioned cases, the pad itself is obtained by punch-pressing of sheets, in order to produce rectangular oblong pieces, which in some cases may have a rounded application extremity. In the case of oblong

rectangular bodies, the sheath or coating of solid jelly has a rounded application or introduction extremity, and preferably it is provided with an axial inlet of a main boring for the passage of the flow and secretions.

5 Both the interior material and the sheath or coating can be perfumed or deodorized, either one of them or both at the same time.

In the drawings:

FIG. 1 shows a top view of the cellulose body, of dehydrated cellulose and pressed in an extra flat shape, which forms part of the pad.

FIG. 2 is a side view according to the previous drawing.

FIG. 3 is a top view of the sheath covering or coating 15 for the cellulose body.

FIG. 4 is a longitudinal sectional view of the mentioned sheath.

FIG. 5 represents a complete perspective view of both elements.

20 FIG. 6 is a longitudinal sectional view of the previous figure.

FIG. 7 shows a top view of the dehydrated pressed cellulose body which is the inner part of the pad, provided with a thread sewn in a longitudinal manner, the 25 free end of which forms the traction thread.

FIG. 8 is a side view, according to the previous figure, in which the loose stitches of the longitudinal thread can be seen, the end of which gives place to the traction thread.

30 FIG. 9 represents a top or plan view of the pad, in which the coating or sheath of jelly has been represented in dot lines, together with its rounded off introduction or application extremity.

In reference to the Figures, it can be seen that they are internal use pads, which comprise a cellulose body 1, dehydrated and pressed, which have an extra flat shape, said body being highly imbibent. The body 1 has a hole 2 on one of its ends or extremities for a traction thread 3, while the opposite end 4 is of a semicircular blunt shape, in the case of FIGS. 1 to 6. The referred body 1 is coated or covered by a sheath 5 of solid vaseline (trademark) or jelly, which sheath is open on its end or extremity 6 and closed on the opposite end 7, this last also being semicircular and rounded. The mentioned coating or sheath 5 is shorter than the body 1 at the end containing the hole 2 and the traction thread 3. The walls of the coating or sheath 5 may be provided with borings 8 for aiding the passage of secretions towards the inner body 1.

45 However, as shown in FIG. 5, this sheath or coating 5 preferably has a continuous outer wall, without borings or openings. In this case, the passage of moisture and secretions towards the body 1 occurs when the sheath or coating is dissolved by body heat after application.

50 In another variation of said invention (FIG. 6), the means by which the moisture and secretions pass through to the absorbent middle body 1 are borings 9 which pass through both the sheath 5 and the body 1, thus forming transversal passages which go into the pad. The rounded end or extremity 7, the nature of the material of the sheath or coating 5, and the extra flatness of the pad, thus make application or introduction of the pad relatively easy.

55 In another variation, corresponding to FIGS. 7 to 9, a rectangular pad which comprises a punched cellulose body 1, or celluloid dehydrated and pressed material

shaped extra flat, is shown. The body 1 is positioned in the interior of a sheath of solid jelly or any jelly-like material 5. The sheath 5 is provided with a rounded end 7, and with an inlet or main bore 10 for the passage of secretions towards the interior of the pad, which pad is highly imbibent or absorbent. The punch-pressed body 1 has a thread 11 sewn in a longitudinal manner, with loose stitches so as to allow for the expansion or swelling of the pad. The excess of thread 12 forms a traction thread loop.

In all these variations of the invention, the flat shape of the pad allows the packing of a great number of same in a minimum space, which also makes its carrying very easy.

The embodiments of the invention in which an exclusive property or privilege is claimed are defined as follows:

1. Improvements in pads for feminine use, of the type for internal application, said pads comprising a dehydrated pressed cellulose body of high moisture absorbent characteristics, said body being thin and flat, said cellulose body being positioned within the interior of an outer covering made of solid jelly-like material and shaped similar to the cellulose body, said covering being circular and rounded adjacent one end of said body, said solid jelly-like material dissolving by the thermic action of the human body, said covering acting as a lubricator for making the application of the pad easier aided at the same time by the flat shape of same, and means for the passage of moisture and secretions to the interior pressed cellulose body, said means including openings which go through the wall of said covering and through the interior cellulose body.

2. Improvements according to claim 1, wherein the other end of said cellulose body is substantially straight,

and a traction thread connected to said cellulose body and projecting outwardly from said other end thereof.

3. Improvements in pads for feminine use, of the type for internal application, said pad comprising a dehydrated pressed cellulose body of high moisture absorbent characteristics, said body being thin and flat, said cellulose body being positioned within the interior of an outer covering made of solid jelly-like material and shaped similar to the cellulose body, said covering being circular and rounded adjacent one end of said body, said solid jelly-like material dissolving by the thermic action of the human body, said covering acting as a lubricator for making the application of the pad easier aided at the same time by the flat shape of same, and a thread sewn in a longitudinal manner to the cellulose body with loose stitches, said thread having an excess portion thereof which projects toward the exterior of the pad and forms a traction thread.

4. Improvements according to claim 3, wherein the covering at its application or insertion end is provided with a central passage which reaches the interior cellulose material, said opening being the main passage for secretions.

5. Improvements according to claim 3, wherein said pad has a thickness which is only a small fraction of the width thereof.

6. A pad according to claim 3, wherein said outer covering includes a pair of spaced and substantially parallel planar sidewalls positioned directly adjacent the opposite sides of said cellulose body, and said outer covering further including a pair of curved edge walls fixedly and integrally connecting the adjacent edges of said sidewalls.
